TELEVISION ANTENNA

Oscar Miller, 4 Overlook Park,
Newton Center, Mass. 02159

Filed Nov. 28, 1967, Ser. No. 9,568

Term of patent 14 years

(Cl. D26—14)

FIG. 1

FIG. 2

FIG. 3

FIG. 4

FIG. 1 is a front view of the television antenna showing my new design;

FIG. 2 is a side elevation thereof;

FIG. 3 is a bottom plan view thereof; and

FIG. 4 is a top plan view thereof.

The dominant features of my design reside in the portions shown in full lines.

I claim:

The ornamental design for a television antenna, as shown and described.
